(57) **CLAIM**

The ornamental design for a combined phone stand and make-up mirror with fill light as shown and described.

DESCRIPTION

FIG. 1 is a front, right and top perspective view of a combined phone stand and make-up mirror with fill light, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 2.

FIG. 10 is an enlarged view of detail 10 in FIG. 2.

FIG. 11 is a perspective view of the combined phone stand and make-up mirror with fill light of FIG. 1 in an alternate configuration of use.

FIG. 12 is a perspective view of the combined phone stand and make-up mirror with fill light of FIG. 1 shown in a folded position; and,

FIG. 13 is another perspective view of the combined phone stand and make-up mirror with fill light of FIG. 12.

The dashed broken lines depict portions of the combined phone stand and make-up mirror with fill light that form no part of the claimed design. The dot-dash broken lines in FIGS. 2, 9, and 10 depict boundaries of enlarged views and form no part of the claimed design.

1 Claim, 13 Drawing Sheets
